UNITED STATES PATENT OFFICE.

THOMAS WHITEHEAD HAWKINS, OF ACREFAIR WORKS, NEAR RUABON, WALES.

MACHINE FOR WASHING WOOL AND OTHER FIBROUS OR TEXTILE MATERIALS OR FABRICS.

Application filed August 23, 1921. Serial No. 494,559.

(GRANTED UNDER THE PROVISIONS OF THE ACT OF MARCH 3, 1921, 41 STAT. L., 1313.)

To all whom it may concern:

Be it known that I, THOMAS WHITEHEAD HAWKINS, a subject of the King of Great Britain, and residing at Acrefair Works, 5 near Ruabon, North Wales, have invented certain new and useful Improvements in Machines for Washing Wool and Other Fibrous or Textile Materials or Fabrics (for which I have filed an application in England 10 No. 25788 dated October 21st, 1919, Patent No. 160485), of which the following is a specification.

This invention relates to machines for washing wools or other fibrous and textile 15 materials and fabrics of the well-known type comprising a single propelling frame for moving the material along the bowl of the machine and extending for practically the whole length of the main bowl and a supplementary discharge frame at the delivery 20 end of the machine for facilitating the removal of the treated material from the machine or from one machine into another when the operation involves the use of a 25 series of machines.

With machines of the above type as hitherto constructed it has been found impossible to deal satisfactorily with different kinds and qualities of materials, and it is the object of the present invention to remedy this 30 defect by providing a machine of the type referred to which is adjustable and adaptable in operation to suit the various materials with which it may be called upon to deal.

The invention consists in a wool washing or like machine of the type referred to in which the propelling frame and the delivery frame are operated by independently adjustable linkage systems driven from separate 40 eccentrics or other driving means.

The invention also consists in a machine of the above character in which means are provided for adjusting the positions of the respective frames independently for the purpose of altering the paths through which the individual members of such frames travel.

The accompanying drawings illustrate one convenient form of machine in accordance with the invention.

50 Figure 1 is a side elevation.

Figure 2 is a fragmentary view showing the frames or rakes and a part of the suspension of the same.

Figure 3 is a plan of Figure 2.

Figures 4 and 5 are respectively front elevation partly in section and a side elevation showing an arrangement of eccentric hereinafter referred to.

In carrying my invention into effect in one convenient manner I provide the wool-washing machine with a main propelling frame *a* and with an auxiliary discharge frame *a'* (Figure 2) of usual or desired construction, the frames being adapted to be suspended from an entablature or frame-work *b* surmounting the whole of the machine.

The auxiliary frame is carried by the rods *b'* and the main frame by the rods *b*². The main frame is connected to the slotted link *c* 70 by the connecting rod *c'* and the auxiliary frame is connected to an independent slotted link *d* by means of a connecting rod *d'* and cross-bar *d*² made slotted as shown in plan in Figure 3 in order to permit of the necessary movements of the rods *b*² passing therethrough.

Each of the linkage systems is driven from its own separate eccentric or other operative member *e*, *f*, and I prefer that each eccentric 80 should be adjustable on its shaft by means of tapered keys *f'* (Figures 4 and 5) curved to fit the shafts on which the eccentrics are mounted or by the adoption of any other known contrivance, such adjustability being 85 for the purpose of varying the paths through which the individual members of the frames may travel, in order to produce the best results as regards the passage of the material being treated through the bowl.

Moreover, the length of stroke of either or both the rakes may be varied as may be desired to suit the particular class or quality of material being treated by altering the positions of the eccentric rod pins in the slotted 90 links *c*, *d*.

It is to be understood that the invention is not limited to the herein described means for operating and separately adjusting the frames, as any equivalent means may be 100 adopted for attaining the same ends.

Having now described my invention, what I claim as new and desire to secure by Letters Patent is:—

1. A machine comprising in combination 105 a single propelling frame for moving the

material along the bowl of the machine and extending for practically the whole length of the main bowl, a supplementary discharge frame at the delivery end of the machine and 5 separately and independently adjustable means for operating each of said frames.

2. A machine comprising in combination a bowl, a single propelling frame extending for practically the whole length thereof, a 10 supplementary discharge frame at the delivery end of the machine, separate linkage systems for actuating said frames and separately and independently adjustable eccentrics for operating said linkage systems.

15 "3. A machine comprising in combination "a bowl a single propelling frame extending "for approximately the whole length thereof, "of, a supplementary discharge frame at the "delivery end of the machine, separate link- 20 "age systems for actuating said frames, sepa- "rately and independently adjustable eccen- "trics for operating said linkage systems and "means by which said systems may be ad- 25 "justed so as to vary the paths through "which the independent members of such "frames travel."

4. A machine comprising in combination a bowl, a single propelling frame extending substantially the whole length thereof, a supplementary discharge frame at the delivery 30 end of the machine, separate linkage systems for suspending and actuating the respective frames and independently adjustable eccentrics for operating the said linkage systems.

5. A machine comprising in combination a bowl, a single propelling frame extending substantially the whole length thereof, a supplementary discharge frame at the delivery 40 end of the machine, independent linkage systems for suspending and operating said frames, independently adjustable eccentrics for operating said linkage systems and means for adjusting the length of stroke of either of said frames.

In testimony whereof I have signed my name to this specification.

THOMAS WHITEHEAD HAWKINS.
